UNITED STATES PATENT OFFICE.

CHARLES H. JOCKMUS, OF ANSONIA, CONNECTICUT.

AUXILIARY AIR-INLET DEVICE FOR INTERNAL-COMBUSTION ENGINES.

1,103,969.

Specification of Letters Patent. Patented July 21, 1914.

Application filed November 17, 1913. Serial No. 801,353.

To all whom it may concern:

Be it known that I, CHARLES H. JOCKMUS, a citizen of the United States, residing at Ansonia, county of New Haven, State of Connecticut, have invented an Improvement 5 in Auxiliary Air-Inlet Devices for Internal-Combustion Engines, of which the following is a specification.

My invention relates to apparatus for supplying preheated air to the cylinder or cylinders of an internal combustion engine, and has particular reference to such apparatus embodying a coil having communication with the cylinder or cylinders and surrounding the exhaust pipe of the engine, said coil being formed of a plurality of turns one of which is provided upon its inner side with an elongated air inlet opening, arranged adjacent the exhaust pipe.

20 An important object of the invention is to provide means of the above-mentioned character, which is simple in construction, inexpensive to manufacture, highly efficient in operation, and durable.

25 Other objects and advantages of the invention will be apparent during the course of the following.

In the accompanying drawings forming a part of this specification and in which like numerals are employed to designate like parts throughout the same.

30 Figure 1 is a side elevation of apparatus embodying the invention; Fig. 2 is a central longitudinal section through a valve structure, parts being in elevation; Fig. 3 is an enlarged edge elevation of a coil removed, and Fig. 4 is an enlarged side elevation of the same, parts being broken away.

35 10 denotes an engine which may have a plurality of cylinders (not shown, as the engine forms no portion of the invention), 40 11 a carbureter, 12 the portion of the intake pipe leading from the carbureter, 13 the horizontal portion of the intake pipe, 14 an intake pipe leading from the horizontal portion to one of the cylinders, 15 an exhaust pipe leading from one of the cylinders and 45 16 the horizontal portion of the exhaust pipe into which a pipe leads from each of the cylinders.

50 17 denotes my novel regulator or valve structure, as a whole, which is attached to and communicates with the portion of the intake pipe leading from the carbureter. 55 Within the regulator or valve structure is a seat 18 engaged by a valve 19 adapted to

slide on a stem 20, the outer end of which is threaded, as at 21, to adapt it for longitudinal adjustment in the head of the regulator. After adjustment the stem is locked 60 in position by a set nut 22. At the inner end of the stem is a head 23. A spring 24 bearing against the head and the valve causes pressure of the valve on the seat, which must be overcome to lift the valve. The regulator is provided with a pet-cock 25 having 65 a nipple to which a rubber tube 26 may be attached.

I supply heated air to the regulator or valve structure by means of a pipe 28 constituting an important feature of the invention, which is connected to the regulator and the other end of which is coiled about the exhaust pipe.

70 It will be noted, see Figs. 3 and 4, that the end of the coil is closed, as at 29 and that the inner face of one of the coils, preferably the end coil is cut away leaving an elongated opening or slot 30 through which air is drawn into the coil. As the coils themselves lie in 75 close proximity to the exhaust pipe, which is highly heated, and the opening is likewise contiguous to the exhaust pipe, it follows that the air drawn into pipe 28 and supplied to the regulator, must necessarily be highly 80 heated.

85 In operation, the valve 19 is opened or unseated by suction from the cylinder or cylinders of the engine. When this valve opens, air is drawn to the cylinder or cylinders through the pipe 28. This air is pre-heated before entering the cylinder or cylinders, the same first passing through the turns in the coiled portion of the pipe, which surround the exhaust-pipe. By having the 90 end of the coil closed, at 29, all the air enters through the slot 30, which is arranged upon the inner side of the turn, whereby a greater 95 heating of the air is obtainable. This also allows of the proper free passage of the air 100 into the turns, said turns providing a long path of travel for the air, retaining the same in proximity to the exhaust pipe for a protracted time, providing proper heating of 105 the air.

Having thus described my invention I claim:-

1. Apparatus for supplying preheated air to the cylinder of an internal combustion engine, embodying a pipe having one end 110 adapted to be placed in communication with the cylinder and its opposite end bent to

form a coil including a plurality of turns to surround the exhaust pipe of the engine, one turn being provided upon its inner side with a longitudinal slot and the opposite 5 end of the pipe being closed, substantially as described.

2. Apparatus for supplying preheated air to the cylinder of an internal combustion engine, embodying a pipe having one end 10 thereof adapted to be placed in communication with the cylinder and its opposite end bent to form a coil including a plurality of turns to receive the exhaust pipe of the engine therein, the end turn being provided 15 upon its inner side with a longitudinal slot and having its end closed, substantially as described.

3. Apparatus for supplying preheated air to the cylinder of an internal combustion engine, comprising a coil including a plurality of turns to receive therethrough the exhaust pipe of the engine, the end turn being provided upon its inner side with a longitudinal slot and having its outer end closed, and means to place the opposite end 20 of the coil in communication with the interior of the cylinder, substantially as described.

In testimony whereof I affix my signature in presence of two witnesses.

CHARLES H. JOCKMUS.
